UNITED STATES PATENT OFFICE.

JOHN KUHL, OF SAN FRANCISCO, CALIFORNIA, ASSIGNOR TO STANDARD OIL COMPANY, OF SAN FRANCISCO, CALIFORNIA, A CORPORATION OF CALIFORNIA.

TANK BREATHER VALVE.

Application filed April 15, 1925. Serial No. 28,254.

This invention relates to tank breather valves and is more particularly directed to pressure and vacuum relief valves for use in connection with containers of volatile fluid.

5 Tanks as now constructed for storing liquids such as petroleum oil and the products of the refining of petroleum oil have for the most part gas-tight sealed roofs, which have introduced a particular problem of providing them with safe and sure means of venting. The air and vapor above the liquid surface is subject to considerable expansion and contraction, with temperature variation, and also as the volume of gas varies with the rise 10 and fall of the liquid surface as the volume of oil in the tank is changed. The nature of the construction of the ordinary storage tank is not such as to withstand the pressure developed by this expansion or contraction 15 without provision for allowing escape and intake of gas or air through the roof. This might be accomplished by means of an open hole in the roof, but this method defeats, in a measure, the purpose of gas-tight tank 20 construction, namely the reduction of vapor losses and fire hazard.

An object of this invention is to provide a means for automatically relieving pressure or vacuum in the tank or other container 30 holding a gas or vapor, which means are so designed that the relief will be effected when the pressure or vacuum reaches a predetermined point.

An object of this invention is to provide a 35 pressure and vacuum relief means which may be placed on the roof of the container, and which means are absolutely fluid-tight until a certain predetermined pressure or vacuum is reached.

40 Other objects and advantages of this invention will be apparent from the following detailed description of a preferred embodiment thereof as illustrated in the accompanying drawings.

45 In the drawings:

Fig. 1 is a diagrammatic side elevation of a vapor line providing a communication between a pair of storage tanks and illustrating an embodiment of this invention.

50 Fig. 2 is a top plan view of a breather valve embodying this invention.

55 Fig. 3 is a similar sectional side elevation of the breather valve illustrated in Fig. 2, illustrating the pressure and vacuum relief valve head in side elevation.

Fig. 4 is a sectional side elevation of one of the relief valves embodying this invention.

Fig. 5 is a fragmental sectional side elevation of the pressure valve illustrated in Fig. 2, illustrating the emergency liquid seal blow-out valve removed and replaced by a cap.

Fig. 6 is a side elevation of the emergency liquid seal blow-out valve embodying this invention, and illustrating the same as attached to a fragment of pipe.

In the embodiment of this invention illustrated in the accompanying drawings, 1 indicates the main body of the breather valve, 2 which body has a screw threaded opening 2 in the bottom for a pipe connection to the tank or other container or system to which the valve is to be connected, the said body 1 having a tapered opening 3 in the bottom 70 for receiving the seats 4 of the vacuum relief valve 5 and making a gas-tight connection between the main body 1 and the valve seat 4, and also having a tapered opening 6 for receiving the seat 4 of the pressure relief 75 valves 5 and making a gas-tight connection between the main body 1 and the seat 4, the body 1 also having a cylindrical bore 7 in the top for receiving the end 8 of the emergency liquid seal blow-out valve 9. A hood 80 10 is secured to the body 1 by any suitable means, such as illustrated at 11. The emergency liquid seal blow-out valve 9 is preferably of the following construction: The body 12 has a central passage or chamber 13 85 around which a circumferential channel 14 is formed, which channel 14 is adapted to be filled with oil or other similar fluid. A cover 15 having a cylindrical extension 16 90 and a curved downwardly extending cap 95 portion 17 is adapted to fit upon the body 12 with the cylindrical portion 16 fitting within the chamber 14 to provide an oil seal. A plurality of equally spaced ribs 18 are provided to rest upon the upper edge of the outer member forming the chamber 14 so as to hold the cover 15 properly spaced from the body 12 so as to provide a fluid passage up through the oil chamber 14 and up under the downwardly extending cap 17. This 100 passage is normally restricted by placing in the channel 14 a suitable fluid such as oil.

It will be seen from the foregoing description that the pressure exerted by the vapors upon the liquid in the channel 14, 110

might push the liquid under the lower edge of the cover 15 and thence upward and out of the channel 14, thereby causing the loss of the liquid and allowing the escape of the vapors at very low pressures. In order to prevent the loss of the liquid and vapors at normal or other pressures not great enough to be dangerous, the channel 14 should be of such depth and the sealing liquid should be of such specific gravity or density that the column of liquid in said channel 14 will not be forced out of the channel at said normal pressures.

The pressure and vacuum relief valves 5 are preferably of similar construction and these valves serve to relieve the pressure or vacuum in the tank or container to which the breather valve is attached or connected whenever the pressure or vacuum reaches a predetermined amount. They can be designed to open at very slight pressure and they have a relatively large relieving capacity without materially increasing the pressure or vacuum in the tank. They have the advantage of being tightly closed and are not likely to stick; therefore the operation of these valves is very reliable.

The valve 5 comprises a cast seat 4 having a groove 19 for holding a fluid, such as mercury, and having a rib 20 with a cylindrical bore 21 which serves as a guide for the valve stem 22. The outside of the valve seats 4 are tapered to fit the openings 3 and 6 in the main body 1, or may be made integral with the body 1. The rib 20 is tapped to receive cap screws 23 for holding the dash pot 24 to the valve seat 4. The valve head is formed of light metal disc 25 which seats into the mercury groove 19. To the center of the disc is secured a valve stem 22 which is preferably in the nature of a hollow tube. To the lower end of the valve stem 22 are attached two wide cylindrical washers 26 between which a guide plate 27 is held. The dash pot 24 is preferably filled with oil or like fluid so that the valve stem 22, the members 26 and the disc plate 27 are immersed. A stop pin 28 passing through the valve stem 22 limits the opening of the valve disc 25 by coming in contact with the lower edge of the bore 21 through which the valve stem 22 passes. This dash pot arrangement serves as the lower guide for the valve stem 22 to prevent the valves 5 from chattering and thereby prevents the blowing out of mercury from the groove 19 and in general insures smooth operation when the valve is opening or closing. The operative pressure or vacuum on the valves 5 is determined by weight of the head 25 together with the weight of the stem 22 and its parts, and is not dependent upon the depth of the seal formed in the mercury.

The valve seats 4 are maintained within the tapered openings 3 and 6 formed in the

body 1 by any suitable or desirable means, such as screw-threading the same into position or the same may be maintained in position by means of a tight tapered fit, the seats 4 being forced into the tapered bores 3 and 6 so that the same will not be dislodged by pressure from within the body 1.

The following illustrative example is given in order to enable those skilled in the art to which my invention pertains to more easily practice the same; it, however, being understood that this example is merely illustrative and subject to wide variations:

I have found that the linear velocity of the vapors escaping through the valves 5 or 9 should be at least 700 feet per minute, in order to prevent a flame from entering the valves and igniting the fluid within the container. The maximum allowable working pressure in any ordinary oil storage tank of any capacity is about one inch of water pressure, or about 5.2 lbs. per square foot above atmospheric pressure.

In the pressure and vacuum relief valves 5, the diameter of channel 19 is approximately $8\frac{3}{4}$ inches; the width of the channel 19 is $\frac{3}{4}$ inch; the depth of channel 19 is $\frac{7}{8}$ inch; the depth of liquid in channel 19 is approximately $\frac{7}{8}$ inch. The liquid used in this channel is mercury of 13.6 specific gravity.

In the emergency relief valve 9, the diameter of channel 14 is approximately 22 inches; the depth of channel 14 is $5\frac{1}{4}$ inches; the depth of liquid in channel 14 is approximately $4\frac{1}{2}$ inches. Liquid used in channel 14 is water or oil of specific gravity of approximately one.

In Fig. 1 is shown the manner in which these breather valves may be used in connection with an oil tank vapor line, which vapor line is the subject of the copending application of John M. Evans, filed November 20, 1924, Serial Number 751,103, where two of such breather valves are shown connected to the top of the tanks A and B, which tanks A and B are connected by means of a vapor line C in such a manner that the excess vapor pressure developed above the surface of the oil in the tank A during the filling of the tank A may be conveyed through the line C to a tank B which is being emptied.

An emergency liquid seal blow-out valve detached from the pressure valve body is illustrated as positioned in the vapor line C.

The operation of this tank breather valve is such that when pressure is developed within the container to which the valve is attached the gas and vapor causing the pressure flows upward through the connection into the body 1 and at a predetermined pressure raises the pressure relief valve 5 to the position illustrated in Fig. 3, or if a sudden or relatively large pressure is developed

within the container the liquid in the circumferential channel 14 may be blown out and the pressure thereby vented to the atmosphere.

- 5 The blowing out of this liquid serves as a warning to the tank field man or other person having charge of the container to which this pressure valve is attached. As soon as the gas pressure is discharged the pressure 10 breather valve 5 re-seats and when the liquid in channel 14 is replaced the tank is maintained closed. In case of a drop in pressure due to a drop of temperature or withdrawal 15 of oil from the tank, a vacuum or reduced pressure is produced therein which reduced pressure is transmitted upward into the pressure valve body 1 and at a predetermined vacuum causes the vacuum relief valve 5 to open and allow air or other suitable gas to 20 flow into the tank and relieve the vacuum, or if a sudden or relatively large vacuum is developed within the container, the liquid in the circumferential channel 14 may be sucked in and the vacuum thereby vented to 25 the atmosphere.

The valve hoods 10 and 15 are constructed with downwardly extending legs or caps to prevent wind and rain from blowing directly against the valve disc 25 in one case 30 and against the liquid seal in the second case, so that the wind or rain will not interfere with the operation of the pressure valve 5 or the chamber 14 of the emergency fluid seal blow-out valve 9.

35 A cover or cap 30 is adapted to tightly fit the bore 7 of the body 1 when it is desired to remove the emergency liquid seal valve 9 to repair the same or when the system to which this breather valve is attached is not 40 such as to require the use of such an emergency valve 9.

Having fully described a preferred embodiment of this invention, it is to be understood that I do not wish to limit this invention to the exact preferred description here-

in disclosed, which may be obviously varied within the scope of the appended claims.

I claim:—

1. A breather valve mechanism adapted to be connected to a fluid containing tank, comprising a body, pressure and vacuum liquid sealed relief valves mounted therein and adapted to relieve a pressure difference between the interior of the tank and the atmosphere of substantially 5.2 pounds per square foot, and an emergency blow-off valve detachably connected to the body and comprising a liquid seal adapted to be broken by the blowing out therefrom of the maintaining liquid when the pressure within the said tank is suddenly increased to a pressure considerably greater than 5.2 pounds per square foot above atmospheric pressure. 50

2. A breather valve adapted to be connected to a fluid container comprising a body providing a fluid chamber, a pressure relief valve mounted in the chamber, a vacuum relief valve mounted in the chamber, the said pressure and vacuum relief valves being adapted to relieve a pressure difference between the interior of the said chamber and the atmosphere of substantially 5.2 pounds per square foot, an emergency valve detachably connected to the said body in open communication with the chamber and comprising a liquid seal, said liquid seal emergency valve including a base portion adapted to contain the liquid maintaining and constituting said liquid seal and a blowoff hood 70 providing a valve head adapted to seat on said liquid containing base portion, said liquid seal being broken by the blowing therefrom of the maintaining liquid where the difference between the pressure in the chamber and that of the atmosphere is increased suddenly to considerably more than 5.2 pounds per square foot. 75

Signed at San Francisco, Calif., this 2nd day of April, 1925.

JOHN KUHL.
